CIRCUIT INTERRUPTER

Leon R. Ludwig, Wilkinsburg, Herbert J. Webb, Forest Hills, and Benjamin P. Baker, Turtle Creek, Pa., assignors to Westinghouse Electric Corporation, East Pittsburgh, Pa., a corporation of Pennsylvania

Application May 24, 1944, Serial No. 537,074

11 Claims. (Cl. 200—148)

1 This invention relates to circuit interrupters, and, more particularly, to circuit interrupters of the fluid blast type.

An object of our invention is to provide an improved circuit interrupter of the fluid blast type which extinguishes the arcs drawn therein in a more effective manner than has been achieved heretofore.

Another object is to more effectively utilize a fluid blast to not only extinguish the main interrupting arcs drawn in a circuit interrupter, but also to more effectively extinguish the arcs drawn by breaking the residual currents through resistors or impedance means which shunt the main interrupting gaps.

Another object is to provide an improved circuit interrupter of the fluid blast type in which the sequence of opening the several gaps is provided in an improved manner.

Another object is to more effectively control the distribution of voltage above and below an orifice through which an arc is drawn to be interrupted.

Another object is to provide an improved circuit interrupter having a shunting resistor in parallel with the main interrupting gap and to utilize the fluid blast employed to interrupt the residual current through the shunting resistor to also operate a conservator which prevents further escape of fluid to the atmosphere following interruption of the main arc and which also maintains a high pressure adjacent the main orifice to thereby maintain a high dielectric strength thereat to minimize the possibility of restriking.

Another object is to provide an improved interlocking valve which prevents the application of closing air to close the disconnect contacts until the voltage is removed from the interrupting gaps by the reclosure of the main contacts.

Further objects and advantages will readily become apparent upon a reading of the following specification taken in conjunction with the accompanying drawings, in which:

Figure 1 is a perspective view of a complete circuit interrupter embodying our invention and shown in the closed circuit position;

Fig. 2 is an enlarged view in vertical cross-section of the left-hand half of the pole unit, it being understood that the right-hand half is of the same construction;

Fig. 3 is a sectional view taken along the line III—III of Fig. 2; and

Fig. 4 is a fragmentary schematic view showing a portion of the operating arrangement.

2 Referring to the drawings and more particularly to Fig. 1 the reference numerals 1, 2 and 3 designate hollow insulator columns supported on a base structure 4, the latter enclosing suitable operating equipment. The hollow insulators 1, 2 and 3 support a housing 5 composed of a conducting material, the latter in turn supporting two additional insulating columns 6 and 7. Disconnect contacts 8, 9 may be retracted into the housing 5 at the completion of an opening operation.

Referring more particularly to Fig. 2 it will be observed that the left-hand hollow insulator column 6 has an annular insulating plate 10 supported at its upper end which provides an orifice 11 defined by an annular ring 12 of conducting material. The plate 10 supports a second annular insulating plate 13, the latter in turn supporting a conducting cylindrical member 14 having integrally formed therewith a spider member 15 and having exhaust apertures 16. The spider member 15 supports the stationary contact 17 which is preferably of the type having segmental fingers biased radially inwardly and serving to make engagement with a movable tubular main contact member 18.

Slidable within the conducting cylindrical member 14 and serving to control the exhaust apertures 16 is a conservator 19 biased downwardly by compression springs 20. The compression springs 20 seat at their upper ends against a conducting cap member 21, the latter secured by bolts 22 to the cylindrical member 14. A weather-proof cylindrical member 23 may be depended from the cap member 21 to prevent rain or snow from entering the exhaust apertures 16. The movable main contact 18 makes sliding contact at 24 with segmental fingers 25, the latter being secured to an outer conducting tube 26 the lower end of which is supported by a cylindrical member 27 composed of a conducting material.

Threadedly secured to the lower end of the movable main contact 18 and operative within the cylindrical member 27 is a piston 28 biased upwardly by a compression spring 29. After the piston has moved down past the point 30 it uncovers by-passing channels 31 which lead to a conduit 32 by means not shown, except schematically in Fig. 4, which is hereinafter described. Bumper 33 supported on a plurality of resilient insulating washer members 34 is provided to cushion the end of the downward stroke of the piston 28. The cylindrical member 27 is threadedly secured at 35 to a casting member 36.

through which passes a rod 31. The rod 31 is slidable through an aperture provided at the lower end of the tubular main contact member 18 and has a nut 38 threadedly secured to its upper end. Apertures 39 are provided at the lower end of the tubular contact 18 adjacent to the aperture through which the rod 31 is slidable. At the lower end of the rod 31 is a cylindrical valve 40 biased downwardly by a compression spring 41 and serving to control openings 42, 43 and 44. The opening 42 leads to atmosphere; the opening 43 leads to the tube 45 (Fig. 4), the latter conducting the closing air of the interrupter. The opening 44 leads to the left-hand end of the disconnect operating cylinder 46 (Fig. 4).

The conduit 32 connects with a dump valve generally designated by the reference numeral 47 by means of a conduit 48. The conduit 32 also leads by means of a conduit 49 to the right-hand end of the disconnect operating cylinder 46. The conduit 32 furthermore connects with a conduit 50 which leads at its right-hand end (Fig. 2) to the hollow insulator 7. The hollow insulator 7 contains concentrically positioned therein a resistor tube 51 having at its upper end a stationary contact 52. Making engagement with the stationary contact 52 is a tubular movable contact 53 having secured thereto at its upper end a piston 54 biased downwardly by a compression spring 55. The piston 54 is movable within a cylindrical member 56 having an aperture 57 at its upper end. The aperture 57 communicates with a tube 58 which leads to a pipe 59, the latter communicating with the region 60 above the conservator 19.

For some applications, it is desirable to provide a resistor R which has a portion r_1 in parallel between the line terminal 61 and the ring 12 defining the orifice 11. The resistor R also has a portion r_2 in parallel between the ring 12 and the casting member 36. The resistor R may be mounted within a third insulating column, if desired, for protection against the weather. For other applications the resistor R need not be used, or the part r_1 may be used without the part r_2 as hereinafter described.

The operation of the circuit interrupter will now be explained. In the closed circuit position of the interrupter, as shown in all the figures, the electrical circuit therethrough proceeds from the line 62 to the line terminal 61, conducting cap member 21, bolts 22, conducting cylindrical member 14, spider member 15, stationary contact 17, movable tubular main contact 18, segmental fingers 25, conducting tube 26, cylindrical member 27, casting member 36, to one terminal of and through the primary winding of a current transformer not shown, but which is enclosed within the hollow insulator column 3. The other terminal of the primary winding makes sliding contact at 63 to the disconnect contact 8. The circuit passes through the right-hand half of the pole unit in an identical manner, to the line 64.

It will be observed that there is a shunting circuit around the contacts 17, 18 by means of the circuit through the resistor 51 in the insulator column 7. This shunt circuit extends from the line terminal 61 through conducting cap member 21, through conducting pipe 59, conducting tube 58, cylindrical member 65, cylindrical member 56, piston 54, tubular contact 53, stationary contact 52, resistor tube 51, conducting stem 66 to housing 5. Thus there are two parallel paths for the

current to flow between the line 62 and the housing 5.

To open the circuit controlled by the circuit interrupter manual means may be operated, or the current transformer may trip on overload an overload contactor and open a valve, not shown, admitting air to conduit 61, which arrangement is not herein disclosed but which is of a type shown in a patent application filed May 24, 1944, Serial No. 537,075, by Leon R. Ludwig, Benjamin P. Baker and James Cumming, now Patent No. 2,447,656, issued August 24, 1948, and which is assigned to the assignee of the instant application.

15 By an actuation of the aforesaid means opening air is caused to pass through the conduit 61 (Fig. 4). The opening air passing through the conduit 61 also passes through conduit 68 to move a piston 69 movable within a piston chamber 70 of the dump valve 47. The air pressure acting through the conduit 68 moves the piston 69 against the biasing action of a compression spring 71 to the left closing the port 72 leading to atmosphere. Thus the movement to the left of piston 69 closes the communication of conduit 48 to atmosphere.

The opening blast air passes through a conduit 73 of the interior of the insulator column 6 where it acts through an aperture 74 (Fig. 2) 30 provided in the cylindrical member 27 to act downwardly on the piston 28. The piston 28 is not moved downwardly by the air pressure to overcome the biasing action of the compression spring 29 until the air is of a sufficient pressure 35 to effect interruption of the arc drawn between the contacts 17, 18. When, however, the air is of this predetermined pressure the piston 28 will be moved downwardly, compressing the compression spring 29 until finally the by-passing channels 31 are uncovered. The air will then pass through the by-passing channels 31, to the conduit 32 leading toward both the disconnect cylinder 46 and the interior of the insulator column 7.

45 By the time that the air pressure acts through the conduit 50, through the insulator column 7, through the aperture 75 to move the piston 54 upwardly compressing the compression spring 55 and drawing an arc between the contacts 52, 53, 50 the arc drawn between the contacts 17, 18 will have been extinguished.

The breaking of the arc between the contacts 17, 18 forces the current to flow through the shunting resistor circuit within the column 7 to not only decrease the rate of rise of the recovery voltage transient but also to lower the amplitude of the recovery transient. Furthermore, the current is greatly reduced in magnitude as a result of having to pass through the resistor tube 51 and the power factor is considerably improved. The residual current passing through the resistor 51 is of a relatively low magnitude and is easily interrupted by a flow of air through the raised movable contact 53, through the aperture 57, through the pipe 59 to the region 60 on top of the conservator 19.

The pressure of the air passing through the pipe 59 is sufficient to reclose the exhaust apertures 16 which were originally opened by the initial application of air through the orifice 11 when interrupting the arc between the contacts 17 and 18. Consequently, the reclosure of the exhaust apertures 16 prevents further escape of gas through the apertures 16 to maintain high pressure in the space between the contacts without

further waste of air. The result is more economical breaker performance.

By the time that the opening air, passing through the conduit 49 to the right-hand end of the disconnect cylinder 46, effects leftward movement of the disconnect piston 76, the arc carrying the residual current passing through the resistor 51 will have been interrupted. As a result the disconnect contacts 8 and 9 are not separated to provide an isolating gap in the electrical circuit until all the arcs are extinguished and the circuit has been interrupted except for the very small current through the resistor R, if it is used.

It will be noted that the region 77 below the orifice 11 is at high pressure and hence is of a high dielectric strength, whereas the region 78 above the orifice 11 is a region of initially low pressure and consequently of low dielectric strength. This is assuring the state of affairs after the conservator has been raised by the initial application of opening air and before the conservator has been closed over the exhaust openings 16 by the air passing through the pipe 59. Thus it is desirable to provide for an impressing of a lower proportion of the total voltage across the contact gap above the orifice than across the contact gap below the orifice 11. We accomplish this by tapping off a small fraction, say $\frac{1}{5}$, of the total value of the resistance R designated r_1 , between the contact 17 and the ring 12, while a greater fraction, say $\frac{4}{5}$, of the resistor R, designated r_2 , is shunted across the ring 12 and the lower segmental contacts 25. By the aforesaid means we control the division of voltage across the orifice 11 to take advantage of the higher dielectric strength of the high pressure gas within the region 77.

For some applications it may be desirable to use only the portion r_1 of resistor R and not to use either the portion r_2 of R or resistor 51 and its associated contact structure 52, 53. In this event, the portion r_1 would effect a rapid interruption of the arc drawn between the stationary contact 17 and the movable contact 18, and the passage of the movable contact 18 below the ring 12 would draw only a residual current arc between the ring 12 and the movable contact 18. This residual current arc drawn between the ring 12 and movable contact 18 would not only be of low amperage but would have a considerably improved power factor and hence would be easily extinguished by the blast of air passing through the orifice 11.

Following the opening of the disconnect contacts 8 and 9 and the closing of the valve supplying conduit 67, a gradual leakage of air past the conservator 19 and through various connections will tend to lower the pressure of air within the insulator column 6 and blast tube 73. Finally the pressure will be sufficiently low to permit the compression spring 71 to force the piston 69 within dump valve 47 to the right opening the exhaust port 72. The opening of the exhaust port 72 will dump the air from the interior of the resistor column 7 and from the right-hand side of the disconnect piston 76. The compression springs 29 in column 6, and 55 in resistor column 7 will thereby effect reclosure of the contacts 17, 18 and 52, 53. Thus after the disconnect contacts 8, 9 have separated to introduce an isolating gap into the circuit following interruption of the arcs, the separable contacts will then reclose to remove voltage across the contact gaps so that the entire voltage impressed across the interrupter will be impressed across the gap produced by the separation of the disconnect contacts 8 and 9.

The circuit interrupter is closed by closing air passing through the conduit 79 (Fig. 4). Fig. 4 schematically shows the operation of the valve 40 of Fig. 2. In other words, upon downward movement of the movable contact 18 the rod 37 will actuate the valve, generally designated by the reference numeral 81 in Fig. 4, to effect thereby a dumping of air from the left-hand end of the disconnect cylinder 46. Thus an opening immediately following a closing of the interrupter will not be retarded by pressure of closing air contained within the left-hand end of the disconnect cylinder 46 retarding the leftward movement of the disconnect piston 76. In other words, referring to Fig. 2, it will be observed that upon downward movement of the movable contact 18 the compression spring 41 will force the cylindrical valve 40 downwardly closing the opening 43 and permitting communication between the exhaust port 42 and the opening 44 leading to the left-hand end of disconnect cylinder 46.

It will also be observed from Fig. 2 that the downward movement of the cylindrical valve 40 permits atmospheric air to enter through the aperture 82 to maintain the region 83 within the casting member 36 at atmospheric pressure. Consequently, there may be some exhaust of air through the movable tubular contact 18 during the interruption of the arc drawn between the contacts 17 and 18. This exhaust of arc products through the movable tubular contact 18, through the apertures 39 and into the region 83 within casting member 36 at atmospheric pressure will facilitate the interruption of the arc drawn between the contacts 17, 18.

It will be observed that following the completion of the opening operation and after reclosure of the contacts 17, 18 and 52, 53 following actuation of the dump valve 47, that the contact 40 actuated valve 81 will be actuated to permit communication between conduit 45, through the valve 81, to the left-hand end of the disconnect cylinder 46. Thus the breaker may be closed by an application of the closing air through the valve 81 into the disconnect cylinder 46 to effect a closing movement to the right of disconnect piston 76 and a consequent reclosure of the disconnect contacts 8 and 9 to effect thereby a completion of the electrical circuit through the interrupter.

It will be observed that the two resistor tubes 51, or other impedance means, associated with the two columns 6 also serve to balance the voltage division between the two series interrupter columns 6 during the interruption process. Thus each half of the pole unit is not required to interrupt more than half the voltage impressed across the entire interrupter. The shunting impedances also cause the circuit rate of rise of recovery voltage to be decreased and at the same time decreases the overshoot of the restored voltage, easing the interrupting duty on the main interrupters 6. It is also apparent that charging currents of low amperage values may more easily be interrupted, for reasons well known in the art.

By reclosing the arcing contacts with springs, the interrupters 6, 7 are short-circuited, and all the applied voltage is placed across the visible outside isolating gap.

An alternative arrangement for using the shunting impedances 51 would be to permanently connect them across the two pairs of main contacts 17, 18. In this event after the arcs drawn between the contacts 17, 18 were extinguished, the residual current drawn by the two impedances

could be interrupted by the disconnect contacts 8, 9.

Such an arrangement may be obtained by using the resistor R, omitting the tap connection 85 and also omitting resistor 51 with its associated contact structure 52, 53.

By varying the value of the resistor tubes 51 the voltage can be divided between the two halves of the interrupter in any desired manner during the interruption process.

Although we have shown and described specific structures it is to be clearly understood that the same were merely for the purpose of illustration, and that changes and modifications may readily be made by those skilled in the art without departing from the spirit and scope of the appended claims.

We claim as our invention:

1. In a circuit interrupter of the gas blast type, means defining an orifice, a stationary contact disposed above the orifice on the low pressure side thereof, a movable contact separable from the stationary contact and movable through the orifice to draw an arc therethrough into the high pressure side of the orifice, a conducting member disposed adjacent to the orifice, and impedance means constantly connected in parallel with the contacts and having a tap connection to the conducting member to control the division of recovery voltage after arc extinction between each of said contacts and said conducting member generally in accordance with the dielectric strength of the gaseous medium on the respective sides of said orifice.

2. In a gas blast circuit interrupter, an arc extinguishing assemblage comprising a main interrupting unit and a parallel connected impedance interrupting unit, means for drawing a main arc in the main interrupting unit, first gas blast means for extinguishing the main arc, means responsive to said first gas blast means for drawing a residual current arc in the impedance interrupting unit after the extinguishing of the main arc, second gas blast means for extinguishing the residual current arc, and means actuated by gas from the second gas blast means to limit escape of gas from the main interrupting unit.

3. In a gas blast circuit interrupter, an arc extinguishing assemblage comprising a main interrupting unit and a parallel connected impedance interrupting unit, piston means operative at a predetermined pressure for drawing a main arc in the main interrupting unit, means comprising a gas blast for extinguishing the main arc, and piston means operative by and in response to the creation of a predetermined blast pressure in said main interrupting unit for drawing a residual current arc in the impedance interrupting unit after the extinguishing of the main arc.

4. In a circuit interrupter of the gas blast type, an arc extinguishing assemblage comprising a main interrupting unit and a parallel connected impedance interrupting unit, means defining an orifice in the main interrupting unit, contact means for drawing a main arc through the orifice, means permitting the flow of a gas blast through the orifice to extinguish the main arc, venting means on the exhaust side of the orifice, a conservator controlling the venting means, means directing gas to flow from said main interrupting unit through the impedance interrupting unit after extinction of the main arc to establish and extinguish a residual current arc in said impedance interrupting unit, and means

utilizing the exhaust gas from said impedance interrupting unit to force the conservator to close the venting means.

5. In a gas blast circuit interrupter, an arc extinguishing assemblage comprising a main interrupting unit and a parallel connected impedance interrupting unit, contact means for drawing a main arc in the main interrupting unit, piston means for actuating the contact means, a by-passing channel uncovered by the piston means only after a predetermined contact separation to permit flow of gas to the impedance interrupting unit, contact means in the impedance interrupting unit for establishing an arc therein, means utilizing the flow of gas to the impedance interrupting unit for assisting extinction of the second-mentioned arc, and means employing gas entering the impedance interrupting unit for limiting the escape of gas from the main interrupting unit.

6. In a gas blast circuit interrupter, an interrupting unit having gas blast directing means including an orifice, stationary contact means disposed on one side of the orifice, a movable contact separable from the stationary contact means and movable through the orifice to draw an arc therethrough, a conducting member lining said orifice, means for causing a blast of gas to flow through said orifice to extinguish the arc, and impedance means connected between the stationary contact means and the conducting member and also between said conducting member and said movable contact to cause the recovery voltage on each side of said orifice following arc extinction to divide generally in accordance with the dielectric strength of the gaseous medium on the respective sides of said orifice.

7. In a circuit interrupter, a pair of terminal members for connecting said interrupter in an electrical circuit, means defining an orifice, separable contact means connected between said terminal members, means for actuating said contact means to open circuit position to establish an arc through said orifice, said contact means having a contact connected to each of said terminal members and disposed on each side of said orifice when said contact means are in the open circuit position, a conducting member adjacent said orifice, means for moving a blast of arc-extinguishing fluid through said orifice to extinguish said arc, and impedance means connected across said terminal members and having a tap connection to said conducting member for controlling the division of voltage from said orifice to each of said contacts following arc extinction generally in accordance with the dielectric strength of the gaseous medium on each side of said orifice.

8. In a circuit interrupter of the gas blast type, a pair of relatively movable contacts operable to open and closed circuit position, means defining a gas passage surrounding said contacts, means positioned between said contacts when in the open circuit position obstructing said passage except for an orifice through which at least one of said contacts is movable to establish an arc, an annular conductor surrounding said orifice, means directing a blast of gas through said passage to extinguish said arc, said passage obstructing means causing a higher gas pressure to be maintained on the inlet side of said orifice than on the exhaust side thereof, impedance means connected across said contacts, and means connecting said annular conductor to an intermediate position along said impedance means to cause

the recovery voltage appearing across said contacts after arc extinction to divide on either side of said orifice generally in accordance with the dielectric strength of the gaseous medium on the respective sides of said orifice.

9. A circuit interrupter of the gas blast type comprising a pair of relatively movable contacts for establishing an arc, gas blast passage means surrounding said contacts, means directing a blast of gas through said passage means to extinguish said arc, pressure responsive means operative to control the flow of exhaust gas from said passage means, said pressure responsive means being operative during arc extinction to permit the escape of gas from said passage means, a resistance connected in parallel with said contacts to limit the rate of rise of the circuit recovery voltage, a second pair of relatively movable contacts in series with said resistance for establishing a residual current arc, a second gas blast passage means surrounding said second pair of contacts, and means responsive to the establishing of a gas blast of predetermined pressure in said first passage means for directing a portion of said gas from said first passage means to said second passage means to extinguish said residual current arc, and means directing the exhaust gas from said second passage means to said pressure responsive means for causing the latter to prevent the further escape of gas from said first passage means.

10. A circuit interrupting structure comprising a first and second fluid passage means, contact structure including a first and second pair of separable contacts respectively disposed in said first and second fluid passage means, a resistance connected in series with said second pair of separable contacts, the first pair of separable contacts being connected in shunt with said resistance and said second pair of separable contacts, means for separating said first pair of contacts to establish an arc, means directing a blast of fluid through said first passage means to extinguish the arc and confine the circuit through said resistance and said second pair of contacts, 45 a pressure responsive conservator associated with said first fluid passage mean for controlling the flow of exhaust gas therefrom, means for separating said second pair of contacts to establish an arc, means directing a blast of fluid through said second fluid passage means to extinguish said last-named arc and finally interrupt the circuit, and means rendering said conservator responsive to the pressure created by the exhaust fluid from said second fluid passage means to prevent the 55 further escape of fluid from said fluid passage means.

11. A circuit interrupter of the gas blast type comprising a pair of relatively movable contacts for establishing an arc, gas blast passage means surrounding said contacts, means directing a blast of gas through said passage means to extinguish said arc, valve means responsive to pressure in both opening and closing directions for controlling the flow of exhaust gas from said passage means, spring means biasing said valve means toward the closed position, an impedance connected in parallel with said contacts to limit the rate of rise of the circuit recovery voltage, a second pair of relatively movable contacts in series with said impedance for establishing a residual current arc, a second gas blast passage means surrounding said second pair of contacts, means responsive to the establishing of a gas blast of predetermined pressure in said first passage means for directing a portion of said gas from said first passage means to said second passage means to extinguish said residual current arc, and a conduit connecting said second passage means with said valve means for causing the exhaust gas from said second passage means to assist said spring means in closing said valve means to prevent the further escape of gas from said first passage means.
